UNITED STATES PATENT OFFICE.

GROSVENOR N. ALLEN, OF ONEIDA, NEW YORK.

DESIGN FOR A SPOON OR SIMILAR ARTICLE.

Application filed December 24, 1926. Serial No. 20,138. Term of patent 14 years.

To all whom it may concern:

Be it known that I, GROSVENOR N. ALLEN, a citizen of the United States, residing at Oneida, county of Madison, State of New York, have invented a new, original, and ornamental Design for a Spoon or Similar Article, fully described and represented in the following specification and the accompanying drawing, forming part of the same, and showing a spoon embodying the design, the essential feature of which is the ornamental matter at the upper end of the spoon. In said drawing Figure 1 is a front view and Figure 2 a rear view of the spoon, while Figure 3 is a section thereof on the line 3—3 of Figure 1.

I claim:

The ornamental design for a spoon or similar article as shown.

In testimony whereof I have hereunto set my hand.

GROSVENOR N. ALLEN.
